Freeman
his ATTORNEY

UNITED STATES PATENT OFFICE.

WILLIAM H. ROSE, OF JERSEY CITY, NEW JERSEY.

CONTAINER CLOSURE.

Application filed July 3, 1924. Serial No. 724,142.

My invention relates to closures and refers particularly to closures adaptable to containers.

In the maintenance and operation of certain classes of liquid containers, as, for instance, those employed for retaining liquid soap, it is essential that some means be employed which will allow of the replenishing of the liquid contents of the container and 10 which will also prevent the container contents from contamination.

It is evident, therefore, that such means must be of a character as will allow of easy access to the interior of the container for 15 purposes of filling and which can be replaced, for purposes of protecting the container contents.

In the generally employed soap containing and dispensing devices, it is usual to employ a 20 metallic plug, stopper, or cap, capable of being inserted within, or caused to cover, the upper open portion, or neck, exit of the container when it is desired to protect the contents, and capable of being withdrawn, or removed, when it is desired to introduce liquids 25 into the container.

These devices, therefore, comprise at least two separable parts, the container and the closure means, and as the closure means are 30 so constructed that their use requires the employment of a key, or similar device, at least, three separable members constitute the generally employed operating means.

These devices have the disadvantage that 35 the loss of one of the separable elements, such as the key, renders the device inoperative.

Another disadvantage of devices of the character described is that the presence of 40 metals is objectionable in many cases, either because the contents of the container attack the metals with which they come in contact, or because the contents cause the several members of the device to adhere together, thus making it difficult, and, at times, 45 impossible, to separate them from each other without breakage.

Many acids and alkalis have the first mentioned effect, while other liquids, and especially liquid soap, possess the property of causing the metallic, or the metallic and glass, or porcelain, members to strongly adhere to each other.

While I have referred particularly to liquid soap containers, my device is not limited to that particular class of container, but can

be employed equally advantageously with other containers, such as collapsible tubes.

My device overcomes all of the above, and other, objectionable features of the described closure means, as will be evident upon a consideration of my specification and accompanying drawings.

Among the advantages and properties of my device are the following:—

It has no separable members, thus overcoming the possibility of the loss of parts with consequent inoperativeness, it requires no special key, or device, for opening, it is easily and rapidly opened and closed, thus 70 saving considerable time in filling the container: the air vent of the device may be made to indicate the place of opening; it is non-metallic, and hence, is not subject to the above-mentioned chemical and physical 75 objectionable features; it is a permanent feature of the container and is removable only with great difficulty, and hence, is not liable to malicious removal; it is positive in action, economical in construction and easy of 80 operation.

The accompanying drawings with their description disclose the value and many advantages of the device of my invention.

In the accompanying drawings, illustrating 85 modified forms of the device of my invention, similar parts are designated by similar numerals.

Figure 1 is a side view of one form of my device employed with a bottom exit soap container and dispenser, partly broken away for 90 purposes of clearness of description.

Figure 2 is a top view of the closure device of Figure 1.

Figure 3 is a bottom view of the closure 95 device of Figure 1.

Figure 4 is a bottom view of a modified form of my closure device.

Figure 5 is a section through the line 5—5 of Figure 4.

Figure 6 is a vertical section showing a modified form of my closure device employed with a collapsible tube.

The particular form of the device of my invention, shown in Figures 1, 2 and 3, comprises a rubber valve disk composed of the annular valve member 10 and the annular flange 11, one portion 12 of the valve member 10 being integral with, or fixedly attached to, the flange 11, the flap, or free portion 13 of the valve member 10 being capable of abutment upon the flange 11. The 105 110

valve flap 13 has a hole, or vent, 14, so positioned that it is not closed by the abutment of the flap 13 upon the flange 11.

A retaining member comprises the internally threaded collar 15 having the inwardly annular flange 16, the diameter of the collar 15 being such that the flange 11 of the valve member will fit snugly therein and the diameter of the opening in the flange 16 is such that it will abut slightly upon the inserted valve member 10 but allow of the forced passage of the valve flap 13 therethrough.

In the drawings, the device is shown attached to a liquid soap dispenser comprising the soap receptacle 17, maintained in fixed upright position by the bracket 18, the liquid contents of the receptacle 17 being allowed to escape through the exit 19 by a pressure upon the valve 20. The neck 21 of the receptacle is externally threaded to mesh with the internal threads of the collar 15.

In assembling the device, the valve disk is inserted within the retaining member and positioned so that the flange 11 abuts firmly upon the inner face of the collar flange 16.

The collar 15 is then screwed upon the neck 21 of the soap dispenser, cement 22 being employed, if desired, in order to make a jointure that can be broken only with difficulty. The collar is screwed downwardly as far as conveniently possible, in order that the pressure of the retainer flange 16 upon the valve flange 11 will force the latter firmly upon the upper face of the receptacle neck 21, thus forming a practically tight jointure.

When it is desired to fill the receptacle 17, the valve flap 13 is pulled outwardly and upwardly, by the insertion of a wire or other suitable device through the vent 14, or other means can be employed for this purpose.

The valve flap 13 is then in the position indicated by the dotted lines of Figure 1.

This allows of a comparatively large free opening in the valve disk through which the liquid may be introduced into the receptacle.

When it is desired to close the receptacle, the valve flap 13 is forced downwardly beneath the retainer collar 16 and is thus held firmly in a closed position.

It is to be noted that, when the device is in closed position, the valve flap 13 abuts upon the upper face of the flange 11, thus preventing its further downward movement.

The vent 14 serves for the admission of air during the withdrawal of the contents of the receptacle 17, and if positioned opposite the fixed, or hinged-like, portion 12 of the valve member, serves as an indicator as to which portion of the valve disk is unattached to the flange 11, and, hence, is the valve flap portion, to be moved for purposes of filling.

In the modification of my device, shown in Figures 4 and 5, the vent 23, instead of being in the valve member 10, as shown

above, is in the valve flange 11 and is capable of alignment with a vent in the retainer collar 16. It is preferable to have the flange vent 23 somewhat elongated, in order to be assured that it is in alignment with the vent 24.

Figure 6 illustrates a modification of my device applied to a collapsible tube 25. In this form of my device, the air vent is omitted, as the valve serves to maintain the material within the tube, a pressure upon the latter forcing the contents against the inner face of the valve flap 13, opening it and allowing the escape of the material, or the valve flap can be opened by other means, as by means of a finger-nail, for instance. When it is desired to close the tube, the valve flap is forced downwardly and, under the retainer collar 16, as described above.

It is obvious that departure may be made from the specific construction, as shown, for instance, the top face of the valve member 10 may be flush with, or below, the top face of the retainer collar 16, or flush with the face of the flange 11, the air vent 14 may be positioned otherwise than as shown, or may be omitted, the retainer 15 may be attached to the container neck 21 other than by screw threads, other means than those shown for preventing the unretarded downward movement of the valve flap 13, and other mechanical changes which are advisable for certain desired containers, or for other purposes to which my device is adaptable.

I do not limit myself to the particular size, shape, number, arrangement, or material of parts as shown and described, as these are given simply as a means for clearly describing the device of my invention.

What I claim is:—

1. In a container closure, in combination, an annular flange and a flap-valve member, a portion of which is integral with the flange and thicker than said flange, the free portion of the valve member abutting upon the flange when in normal position.
2. In a container closure, in combination, an annular flange, a flap-valve member, a portion of which is integral with the flange and thicker than said flange, the free portion of the valve member abutting upon the flange when in normal position and an air opening in the valve member.
3. In a container closure, in combination, an annular flange, a flap-valve member, a portion of which is integral with the flange and thicker than said flange, the free portion of the valve member being thinner than the integral portion abutting upon the flange when in normal position and means for attaching the device across a container opening.
4. In a container closure, in combination, an annular flange, a flap-valve member, a

portion of which is integral with the flange and thicker than said flange, the free portion of the valve member being thinner than the integral portion, an air opening in the device and means for attaching the device across a container opening abutting upon the flange when in normal position.

5. In a container closure, in combination, an annular flange, a flap-valve member, a

portion of which is integral with the flange and thicker than said flange, the free portion of the valve member being thinner than the integral portion abutting upon the flange when in normal position. 20

Signed at New York city in the county 25
of New York and State of New York this
1st day of July, 1924.

WILLIAM H. ROSE.
